The present invention relates to an improved method of separating acetylene from gas mixtures.

For the separation of acetylene from gas mixtures, in particular those which have been obtained by thermal or electrical cracking of hydrocarbons with or without oxygen, processes are known according to which the acetylene is washed out from the gas mixture by a solvent. In order to be able to absorb the largest possible amounts of acetylene, this washing is carried out under increased pressure. If the gas is put under pressure, however, difficulties are encountered, chief among which are the following: black deposits will form on the suction valves of the compressor and affect the functioning of the valves after some time; incrustations of more or less dark coloration will form in the cooling devices of the compressor, reduce the cooling effect and even clog the condenser tubes after some time. These incrustations can only be removed by mechanical means. According to our knowledge these incrustations partly consist of polycyclic hydrocarbons, as for example naphthalene, β -methylnaphthalene, acenaphthene, and acenaphthylene. The said shortcomings can be remedied by subjecting the gas to a pre-wash treatment with a solvent capable of absorbing the said contaminants. Thus, it has heretofore already been proposed to strip the gas of diacetylene with a solvent prior to compression. Wherever solvents have been used for a pre-wash of a gas, they had to be stripped from the gas separately in order to be re-used in a cycle.

We have now found that the separation of acetylene can be carried out in a simpler manner while avoiding the said disadvantages and with only one solvent by working in two stages, a smaller amount of the solvent being used in the first stage at atmospheric pressure or at the pressure at which the gas mixture is formed or slightly above the same, and a larger amount of the same solvent being used in the second stage at a higher pressure than in the first stage. The washing liquids are freed from the absorbed substances in the usual way by releasing the pressure and degassing, preferably at elevated temperature and sub-atmospheric pressure, and used again for the washing. Since the same solvent is used in both stages, the working up of the laden washing liquids can be carried out together so that the process is simplified considerably.

The washing in the two stages is preferably carried out at room temperature. In the first stage atmospheric or only slightly, for instance up to 1.5 atmospheres, increased pressure is used. The pressure is determined by the necessity that the temperature may not fall below the dew point of the said polycyclic hydrocarbons. A pressure less than one atmosphere absolute is also applicable, but a pressure below atmospheric pressure will feasibly be avoided in practical operation in view of sucking in air and having to compress a mixture of acetylene and oxygen which might cause danger of explosion. If the acetylene-containing gas has been obtained by a process which

2

operates under pressure, the washing can be carried out at this pressure or a slightly higher pressure. In the second stage the pressure is higher; it may lie for example between about 8 and 30 atmospheres. The lower pressure limit is mainly dependent upon economic considerations, the quantities of solvent to be circulated being too large when employing too low a pressure. The upper pressure limit is determined by the necessity for the partial pressure of the acetylene being not higher than that to which acetylene can be compressed without danger of explosion. The pressure limits, as a result, are also determined by the composition of the gas mixture, i. e. by the percentage of acetylenes.

The amount of washing liquid which is necessary in the first stage is only a small fraction of the washing liquid which is used in the main washing in the second stage. As a rule, for the preliminary washing in the first stage, less than 2% of the amount of washing agent used in the second stage is sufficient. The amount of solvent used in the first stage is preferably an amount just sufficient to recover substances harmful to high-pressure operation while absorbing only a small quantity of acetylene and a minor part of the diacetylene present in the gas mixture. Optimum quantities of solvent can be readily determined by simple experimentation. To obviate the said difficulties the said polycyclic hydrocarbons which melt at a temperature lying above that of the cooling water used, need only be washed out to such an extent that the temperature under the prevailing pressure conditions, does not fall below the dew point.

Solvents suitable in the practice of our invention are such organic solvents with a boiling point higher, for example, than 150° C. and a high solvent power for acetylene, as are stable thermically and at least partially miscible with water, as for example butyrolactone and N-methylpyrrolidone.

The separation of the acetylene from the laden washing liquid is effected in the usual way by releasing the pressure, for example to atmospheric pressure, and also by 40 gassing out with the aid of pure acetylene, for example acetylene obtained from the process, and if desired by further gassing out at elevated temperature and/or at reduced pressure. It is advantageous to use several stages when degassing and to remove first the gases which have 45 a lower solubility coefficient than acetylene.

The washing liquid freed from acetylene is returned to the two washing stages. It is preferable to branch off a small portion and to remove therefrom, for example by distillation, the constituents absorbed thereby which are 50 not separable by degassing. The washing liquid thus purified, if desired together with a part of the liquid which has only been degassed, is used for the preliminary washing in the first stage.

The washing liquid withdrawn from the first stage, 55 without previous degassing, can also be freed by distillation from the constituents not separable by degassing and returned to the two washing stages either alone or together with degassed washing liquid.

The invention will now be described with reference to 60 the accompanying drawings which illustrate diagrammatically by way of example three embodiments of the process according to this invention. Similar parts are designated by similar letters in each of the drawings.

Referring to Figure 1, an acetylene-containing gas mixture is led at atmospheric pressure through a pipe A into a washing tower B into which a solvent for acetylene is charged at the top through a pipe C. The solvent laden with impurities and some acetylene leaves the washing tower B through a pipe R which conducts it toward the 65 degassing tower O.

The preliminarily purified gas mixture is led from the

tower B through a pipe D to a compressor Z from which it passes into a washing tower E. The bulk of the solvent for the acetylene is supplied to this tower through a pipe F. The laden washing liquid is withdrawn through a pipe H and led into a rectification tower I while being released from pressure through an expansion valve V. In this tower there takes place a separation of the gases dissolved in the washing liquid into pure acetylene which is withdrawn through a pipe M and gases with a smaller solubility coefficient than acetylene which escape through a pipe L and are supplied to the compressor Z.

The washing liquid leaves the tower I through a pipe N and, after it has been combined with the washing liquid flowing from the preliminary washing tower B through the pipe R, passes to the degassing tower O. From this the residual gas escapes through a pipe K and is led into the lower part of the rectification tower I. The constituents which have a higher solubility coefficient than acetylene escape from the degassing tower O through a pipe P.

The washing liquid freed from acetylene and other readily soluble constituents leaves the degassing tower O through a pipe Q and passes through pipes F and C to the washing towers E and B.

Figure 2 shows the same process but in which a part of the degassed washing liquid, leaving the degassing tower O, is branched off, freed in the vessel S from substances which have not been removed by the degassing (these are withdrawn through a pipe U) and supplied through pipes T and C to the first washing stage B. The portion of the washing liquid which has only been degassed and which leaves the degassing tower O through the pipe Q, is led to the second washing stage E and partly to the first washing stage B.

According to Figure 3, the washing liquid laden in the first washing stage is led through the pipe R, if desired together with a portion of the washing liquid leaving the degassing tower O, to the treatment plant S and thence, after separation of the constituents not removable by degassing, to the washing stages E and B together with the washing liquid which has only been degassed from the degassing tower O.

The following examples, given with reference to Figure 2, will further illustrate this invention but the invention is not restricted to these examples. Parts are parts by weight unless otherwise specified.

Example 1

By incomplete combustion of methane a gas mixture of the following average percentage-by volume composition is produced:

Acetylene	8.15
C_3H_4 -hydrocarbons	0.1
Diacetylene	0.12
Benzene	0.03
Ethylene	0.3
Methane	4.1
Carbon dioxide	3.5
Oxygen	0.1
Carbon monoxide	26.0
Hydrogen	56.7
Nitrogen plus argon	0.9

In addition the mixture contains the following contaminants in grams per cubic meter:

Phenylacetylene	0.11
Naphthalene	0.20
Acenaphthene	0.04
Acenaphthylene	0.06

Using a plant system as illustrated in Figure 2 of the diagrammatic drawing annexed 100 cubic meters of the said gas is passed through line A into the pre-washer B at a pressure of 1.1 atmospheres absolute and a temperature of $19^\circ C$, 2 kilograms of butyrolactone being simul-

taneously fed in through line C. From line D a gas of the following average percentage-by volume composition is withdrawn:

Acetylene	8.14
C_3H_4 -hydrocarbons	0.1
Diacetylene	0.11
Benzene	0.02
Ethylene	0.3
Methane	4.1
Carbon dioxide	3.5
Oxygen	0.1
Carbon monoxide	26.0
Hydrogen	56.73
Nitrogen plus argon	0.9

In addition the gas contains the following substances in grams per cubic meter:

Phenylacetylene	0.09
Naphthalene, circa	0.02
Acenaphthene	<0.01
Acenaphthylene	<0.01

As a result, about 10% of diacetylene, about 20-30% of benzene and phenylacetylene, about 90% of naphthalene and at least 90% of acenaphthene and acenaphthylene have been removed.

The pre-washed gas is compressed to a pressure of 9 atmospheres absolute in a compressor Z. The compressor and the condensers attached to it remain perfectly clean, apart from a faint film of carbon black, even after an operation for weeks, while in the absence of a pre-wash stage deposits of carbon black and naphthalene will form after a few hours in the compressor and especially in the condensers resulting in a decrease in the efficiency of the compressor and the cooling effect of the condensers after a two weeks' operation. These deposits can only be removed by mechanical means.

The gas mixture compressed to 9 atmospheres absolute then passes to the scrubber E into which 1150 kilograms of butyrolactone are fed overhead through line F at a temperature of $23^\circ C$. Through line G 91 cubic meters of a gas having the following average percentage-by volume composition are withdrawn:

Acetylene	0.1
Ethylene	0.3
Methane	4.5
Carbon dioxide	3.8
Oxygen	0.1
Carbon monoxide	28.3
Hydrogen	61.8
Nitrogen plus argon	1.1

No polycyclic hydrocarbons and higher acetylenes can be identified.

The washing agent laden with acetylene and part of the other constituents contained in the crude gas leaves the tower E through the pipe H and passes into the rectification tower I and thence through the pipe N into the degassing tower O whereby heating to $100^\circ C$. and reducing the pressure to 0.2 atmosphere the dissolved gases are set free. The liberated gases pass through the pipe K into the lower end of the rectification column I in which they flow in counter-current to the solvent. A part of the acetylene with the gases expelled from the solution leave the tower I through the pipe L and are supplied to the suction side of the compressor Z. 7.9 cubic meters of acetylene which contains about 0.1% of C_3H_4 -hydrocarbons less than 0.1% of carbon dioxide, less than 0.02% of diacetylene and less than 0.01% of benzene, are withdrawn through the pipe M. No polycyclic hydrocarbons can be identified. The gas constituents of better solubility than acetylene escape from the degassing tower O through the pipe P. In the said gas, in addition to small quantities of acetylene, the following compositions are detected: methylacetylene, relatively large

proportions of diacetylene, phenylacetylene, naphthalene, acenaphthene, and acenaphthylene.

The solvent which has been degassed in the degassing tower O is for the most part returned to the washer E through the pipe Q while a smaller partial stream is subjected to a distillation in the tower S. The solvent distilled over, after condensation and cooling, is returned through the pipe T to the tower B and if desired supplemented by solvent from the pipe Q. The impurities incapable of distillation in the tower S are withdrawn through the pipe U.

Example 2

By incomplete combustion of methane a gas mixture of the following average percentage-by volume composition is produced:

Acetylene	8.65
C_3H_4 -hydrocarbons	0.1
Diacetylene	0.17
Benzene	0.08
Ethylene	0.3
Methane	5.2
Carbon dioxide	3.6
Oxygen	0.12
Carbon monoxide	24.9
Hydrogen	55.8
Nitrogen plus argon	1.1

In addition the mixture contains the following contaminants in grams per cubic meter:

Phenylacetylene	0.21
Naphthalene	0.36
Acenaphthene	0.10
Acenaphthylene	0.27
Pyrene	0.001

Using a plant system as illustrated in Figure 2, 100 cubic meters of the said gas are passed through line A to the pre-washer B at a pressure of 1.05 atmospheres absolute and a temperature of 25° C., 4.9 kilograms of N-methylpyrrolidone being supplied through line C. The gas withdrawn from line D has the following average percentage-by volume composition:

Acetylene	8.63
C_3H_4 -hydrocarbons	0.1
Diacetylene	0.11
Benzene	0.06
Ethylene	0.3
Methane	5.2
Carbon dioxide	3.6
Oxygen	0.1
Carbon monoxide	24.9
Hydrogen	55.9
Nitrogen plus argon	1.1

In addition the mixture contains the following contaminants in grams per cubic meter:

Phenylacetylene	0.15
Naphthalene	0.03
Acenaphthene	<0.01
Acenaphthylene	<0.01
Pyrene	not identifiable.

As a result, about 30% of diacetylene, of benzene and of phenylacetylene and about 90% of naphthalene, of acenaphthene and of acenaphthylene have been removed.

The gas mixture is then compressed to 13 atmospheres absolute in the compressor Z. Both the compressor and the condensers attached thereto, apart from a faint film of carbon black, remain perfectly clean even after an operation for weeks.

The compressed gas mixture is then scrubbed with 450 kilograms of N-methylpyrrolidone in the scrubber E. The result is substantially the same as that obtained in Example 1, except that 8.4 cubic meters of acetylene with

about 0.1% of C_3H_4 -hydrocarbons, less than 0.1% of carbon dioxide, less than 0.01% of diacetylene and less than 0.005% of benzene are obtained.

We claim:

1. An improved process for the separation of acetylene from a gas mixture containing acetylene and obtained by cracking hydrocarbons which comprises washing said gas mixture containing polycyclic hydrocarbon contaminants in a first stage with an amount of acetylene-absorbing solvent and at a pressure between about atmospheric and 1.5 atmospheres, which amount and pressure are sufficiently low that only a small quantity of acetylene and diacetylene but the bulk of said contaminants is absorbed, washing the gas from the first stage in a second stage with a larger amount of the same solvent and at a pressure between about 8 and 30 atmospheres so as to absorb substantially the remainder of said acetylene, removing substantially pure acetylene from the solvent used in the second stage, combining said solvent freed of acetylene with the solvent from the first stage, the latter containing a small quantity of acetylene and diacetylene and said polycyclic hydrocarbon contaminants, removing the absorbed substances from the combined first stage and second stage solvent, and recycling the solvent substantially free from absorbed substances to said first and second stages for further washings.

2. A process as claimed in claim 1 wherein the pressure in the first stage is of the same range as the pressure under which the acetylene containing gas mixture has been obtained.

3. A process as claimed in claim 1 wherein the amount of solvent employed in the first stage is less than 2 percent of the amount of solvent employed in the second stage.

4. A process as claimed in claim 1 wherein the solvent employed is butyrolactone.

5. A process as claimed in claim 1 wherein the solvent employed is N-methylpyrrolidone.

6. A process as claimed in claim 1 wherein the removal of absorbed substances from the combined first and second stage solvent includes a degassing, at least part of the degassed solvent returned to the second stage washing, the remaining degassed solvent distilled to remove absorbed constituents not separable by degassing, and the distilled solvent returned to the first stage.

7. An improved process for the separation of acetylene from a gas mixture containing acetylene and obtained by cracking hydrocarbons which comprises washing said gas mixture containing polycyclic hydrocarbon contaminants in a first stage with an amount of acetylene-absorbing solvent and at a pressure between about atmospheric and 1.5 atmospheres, which amount and pressure are sufficiently low that only a small quantity of acetylene and diacetylene, but the bulk of said contaminants are absorbed, washing the solvent from the first stage in a second stage with a larger amount of the same solvent and at a pressure between about 8 and 30 atmospheres so as to absorb acetylene, rectifying the solvent from the second stage to free pure acetylene, degassing the rectified solvent from the second stage, distilling at least part of the solvent from at least one of the two stages to free absorbed constituents not separable by degassing, and reusing both degassed and distilled solvent for washing in each of the two stages.
